United States Patent Office

Des. 212,368
Patented Oct. 8, 1968

212,368

COMBINED RAZOR AND BLADE HOLDER

Robert D. Bowman, 1308 Ocean Park Blvd., Apt. 3,
Santa Monica, Calif. 90405

Filed Nov. 20, 1967, Ser. No. 9,465

Term of patent 14 years

(Cl. D33—23)

FIG. 1.

FIG. 2.

FIG. 1 is a perspective view taken from the top, front and one side of a combined razor and blade holder showing my new design.

FIG. 2 is a perspective view taken from the bottom, rear and side opposite that shown in FIG. 1.

I claim:

The ornamental design for a combined razor and blade holder, as shown.
